CLAIM

The ornamental design for a combined headset and watch, as shown and described.

DESCRIPTION

FIG. 1 is a front perspective view of a combined headset and watch, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view of the combined headset and watch;

FIG. 8 is an enlarged bottom plan view thereof; and,

FIG. 9 is another perspective view of the combined headset and watch shown in an alternate configuration.

The broken lines in the drawings illustrate portions of the combined headset and watch that form no part of the claimed design.
